(57) **CLAIM**

The ornamental design for a television receiver frame, as shown and described.

DESCRIPTION

FIG. 1 is a front perspective view of a television receiver frame;

FIG. 2 is a front view of the television receiver frame of FIG. 1;

FIG. 3 is a rear view of the television receiver frame of FIG. 1;

FIG. 4 is a left-side view of the television receiver frame of FIG. 1;

FIG. 5 is a right-side view of the television receiver frame of FIG. 1;

FIG. 6 is a top plan view of the television receiver frame of FIG. 1;

FIG. 7 is a bottom plan view of the television receiver frame of FIG. 1; and,

FIG. 8 is a rear perspective view of the television receiver frame of FIG. 1.

Features shown in broken lines in FIGS. 1, 2, 3, 4, 5, and 7, form no part of the claimed design.
